Attorneys

UNITED STATES PATENT OFFICE.

WALTER L. CHURCH, OF HOUSTON, TEXAS.

PUMP.

Application filed April 7, 1924. Serial No. 704,646.

To all whom it may concern:

Be it known that I, WALTER L. CHURCH, a citizen of the United States, residing at Houston, in the county of Harris and State 5 of Texas, have invented certain new and useful Improvements in a Pump, of which the following is a specification.

This invention relates to new and useful improvements in a pump.

One object of the invention is to provide 10 in a pump, a novel means for connecting the sucker rod to the traveling valve, whereby said rod may be readily attached to the traveling valve in the well, and as readily detached therefrom, and withdrawn leaving said valve in the working barrel.

Another object of the invention is to provide 15 in a pump a novel form of separable coupling whereby two parts or sections may be connected together, for simultaneous movement or disconnected.

With the above and other objects in view this invention has particular relation to certain novel features of construction, operation, 20 and arrangement of parts, an example of which is given in this specification and illustrated in the accompanying drawings, wherein:—

Figures 1 and 2, respectively, show fragmentary side elevations, partly in section, of the upper and lower parts of the working barrel, with the traveling and standing valves therein.

Figures 3 and 4 show side elevations 25 partly in section, of the upper and lower ends, respectively of the means for connecting the sucker rod to, and disengaging it from, the traveling valve.

Figure 5 shows a cross sectional view 30 thereof, taken on the line 5—5 of Figure 4, and

Figure 6 shows a cross sectional view taken on the line 6—6 of Figure 4.

Referring now more particularly to the 35 drawings, wherein like numerals of reference designate similar parts in each of the figures, the numeral 1 designates the working barrel of the pump, which is suspended in the well bore by the pump tubing which extends to the surface of the ground in the usual way.

Located in the lower end of the barrel there is the usual standing valve (not fully shown) which is equipped with the valve cage 4, having the upstanding, outwardly threaded nipple 5 which has the nut 6

threaded onto the upper end thereof, and whose upper face 7, is preferably knurled, or toothed.

Above the standing valve there is a traveling valve, or plunger. This plunger has the 60 inner tubular barrel 8 with the upper and lower nipples 9 and 10, threaded thereon. The nipple 10 clamps the valve seat 11 between it and the lower end of the barrel 8, which is controlled by the upwardly opening ball valve 12. A cross pin 13 in the barrel 8, above the valve 12, limits the upward movement of said valve. The lower end of the nipple 10 is contracted and downwardly extended forming the tubular coupling member 14 which is internally threaded, 65 and provided with the side ports 15, 15, above the threads.

On the upper end of the nipple 9 there is the valve seat 16 which is clamped in place 75 by the valve cage 17, screwed onto the upper end of the nipple 9. An upwardly opening valve 18 controls the seat 16 and is confined by the cage 17. The upper end of this cage has an upwardly extending blank neck 19. 80

On the barrel 8, and clamped between the nipples 9 and 10, there is a sectional liner 20, preferably formed of cast iron but which may be made of steel, if desired.

In order to connect the sucker rod to the 85 traveling valve, I have provided a connecting rod 21 whose upper end is outwardly threaded to receive the lower end of the sucker rod. There is a sectional tubular housing 22 whose upper end has an inwardly turned flange 23 forming a bearing through 90 which said rod extends. This rod has the annular shoulders 24 and 25 above and below said bearing, respectively.

The lower end of the rod 21 is outwardly 95 threaded to receive the nut 26 which is screwed onto the lower end thereof, and whose lower end is toothed. The lower end of the housing 22 has an inwardly converging seat 27, and within said lower end there is a tubular clamp member 28 whose upper end is internally threaded, and whose lower end is slotted forming the clamp jaws 29 whose inner faces are toothed, and whose lower ends are inwardly beveled to conform 100 to the shape of the seat 27. In operation the upper end of the neck 19 of the traveling valve is clamped and held by the jaws 29, said jaws being held contracted around said 105 neck by the converging seat 27. While in 110

this position the upper end of the neck 19 abuts against the stop 31 within said clamp member.

In some cases the working barrel 1 is of a greater inside diameter than the well tubing to which said barrel is attached, and in such cases the traveling valve will not pass up through said tubing. It is then necessary to detach the sucker rod from the traveling

10 valve. In order to accomplish this the sucker rod is lowered until the nut 26 rests upon the upper end of the clamp member 28, and turned to the right. The friction of the nut against said member will hold the nut stationary and the lower end of the rod 21 will be threaded into the upper end of the clamp member. The shoulder 24, of the rod will now rest upon the upper end of the housing 22 and as the rod is screwed further 15 into said clamp member it will be elevated and the jaws will be unseated from the seat 27, and will expand to release the neck 19 of the traveling valve, and the sucker rod may then be withdrawn from the well.

20 25 This form of separable coupling is capable of general use and may be employed for purposes other than merely connecting a sucker rod to the traveling valve of a pump.

What I claim is:—

30 35 40 45 1. In a pump a plunger having an upwardly extending neck, a tubular housing whose lower end is contracted forming a tapering seat and whose upper end is formed with a bearing, a clamped member in the housing whose lower end is formed with expandible jaws, adapted to be contracted by said seat into engagement with said neck, a rod working through said bearing and formed with an abutment above and below said bearing, said clamp member and rod being formed one with an outwardly threaded neck and the other with an inwardly threaded socket adapted to receive said threaded neck to connect said rod and clamp member together.

50 55 60 65 2. In a pump a plunger having an upwardly extending neck, a tubular housing whose lower end is contracted forming a tapering seat and whose upper end is formed with a bearing, a clamp member in the housing whose lower end is formed with expandible jaws, adapted to be contracted by said seat into engagement with said neck, a rod working through said bearing and formed with an abutment above and below said bearing, said clamp member and rod being formed one with an outwardly threaded neck and the other with an inwardly threaded socket adapted to receive said threaded neck to connect said rod and clamp member together, and a nut on said threaded neck.

70 75 80 85 3. In a pump a connecting device including a tubular housing formed at its upper end with a bearing, a rod slidable through said bearing and having two abutments, one

above and the other below the bearing, the lower end of the housing being contracted, forming a tapering seat, a tubular clamp member in the housing, whose lower end is formed into clamp jaws which normally 70 rest on said seat.

4. In a pump, a tubular housing having a bearing at one end, a tapering seat at the other end of the housing, a clamp member in the housing, expandible grip jaws carried by said member having tapered portions adapted to rest on said seat, a rod working through said bearing, abutments on said rod on opposite sides of the bearing, said rod and clamp member being formed, 75 one with an internally threaded socket and the other with an externally threaded neck adapted to be screwed into said socket.

5. In a pump a tubular housing having a bearing at one end, a tapering seat at the 80 other end of the housing, a clamp member in the housing, expandible grip jaws carried by said member having tapered portions adapted to rest on said seat, a rod working through said bearing, abutments on said rod on opposite sides of the bearing, said rod and clamp member being formed, one with an internally threaded socket and the other with an externally threaded neck adapted to be screwed into said socket.

90 95 100 105 6. In a pump a connecting device including a tubular housing whose lower end is contracted forming a tapering seat, a tubular clamp member in the housing whose lower end is formed with clamp jaws which normally rests on said seat, a rod slidable in said housing above said clamp member, means for limiting the movement of said rod relative to said housing.

110 115 120 125 7. In a pump a connecting device including a tubular housing whose lower end is contracted forming a tapering seat, a tubular clamp member in the housing whose lower end is formed with clamp jaws which normally rests on said seat, a rod slidable in said housing above said clamp member, means for limiting the movement of said rod relative to said housing, said rod and clamp member being formed with means whereby they may be interlocked together.

8. In a pump a connecting device including a tubular housing whose lower end is contracted forming a tapering seat, a tubular clamp member in the housing whose lower end is formed with clamp jaws which normally rests on said seat, a rod slidable in said housing above said clamp member, means for limiting the movement of said rod relative to said housing, said rod and clamp member being formed, one with an internally threaded socket and the other with an externally threaded neck adapted to be screwed into said socket.

9. In a pump a connecting device includ-

ing a tubular housing whose lower end is contracted forming a tapering seat, a tubular clamp member in the housing whose lower end is formed with clamp jaws which 5 normally rests on said seat, a rod slidable in said housing above said clamp member, means for limiting the movement of said rod relative to said housing, said rod and clamp member being formed, one with an internally threaded socket and the other with an externally threaded neck adapted to be screwed into said socket, and a nut 10 threaded onto said neck.

10. In a separable coupling a housing one 15 end of which is formed with a converging seat, a clamp member in the housing, clamp jaws carried by said clamp member arranged to rest on said seat, an actuating member slidable in the other end of the 20 housing, means for limiting the range of movement of said actuating member relative to the housing, said actuating member

and clamp being formed with means whereby they may be interlocked together.

11. In a separable coupling a housing one 25 end of which is formed with a converging seat, a clamp member in the housing, clamp jaws carried by said clamp member arranged to rest on said seat, an actuating member slidable in the other end of the 30 housing, means for limiting the range of movement of said actuating member relative to the housing, said actuating member and clamp being formed with means whereby they may be interlocked together, and a 35 stop within said clamp member.

In testimony whereof I have signed my name to this specification in the presence of two subscribing witnesses.

WALTER L. CHURCH.
